PEN

Pietro Gulizia, Chicago, Ill.

Application August 20, 1934, Serial No. 740,687

3 Claims. (Cl. 120—47)

This invention relates generally to pens, and more particularly to a novel and improved construction of a pen of the fountain type.

It is an object of this invention to provide a pen of the character described having novel and improved means for filling the same, which means will permit said pen to hold a supply of ink substantially four times as large as that possible with pens heretofore used.

10. Another object of this invention is to provide in a pen of the character described the novel and improved means for drawing a supply of ink into the same, said means being simple in operation and requiring only a few parts which will 15 not readily get out of order.

A further object of this invention is to provide a pen of the character described having novel and improved means for filling the same, the said means occupying a comparatively small 20 space within the pen barrel, thereby permitting the said barrel to hold a relatively large supply of ink and being constructed of only a few parts which will not become inoperative and get out of order in use.

25. A still further object of this invention is to provide a pen of the character described comprising only a few parts which may be readily assembled and disassembled and which is provided with novel and improved means for filling the same in addition to novel and simplified means for actuating said filling means.

30. A still further object of this invention is to provide a pen of the character described which will be simple in construction comprising only a few parts readily assembled in operative position and which may be produced along lines convenient for low cost manufacture while at the same time being highly efficient for carrying out the purpose for which it is designed.

40. With the foregoing and other objects in view which appear as the description proceeds, the invention consists in certain novel features of construction, arrangement and combination of parts hereinafter more fully described, illustrated 45 in the accompanying drawing and particularly pointed out in the appended claims, it being understood that various changes in the form, proportion, size and minor details of the structure may be made without departing from the spirit or sacrificing any of the advantages of the invention.

45. For the purpose of facilitating an understanding of my invention, I have illustrated in the accompanying drawing a preferred embodiment thereof, from an inspection of which when con-

sidered in connection with the following description, my invention, its mode of construction, assembly and operation, and many of its advantages should be readily understood and appreciated.

5. Referring to the drawing in which the same characters of reference are employed to indicate corresponding or similar parts throughout the several figures of the drawing:

Fig. 1 is a longitudinal sectional view through a pen embodying my invention;

Fig. 2 is a plan view taken on line 2—2 of Fig. 1;

Fig. 3 is a transverse sectional view taken on line 3—3 of Fig. 1;

Fig. 4 is a sectional view taken on line 4—4 of Fig. 1;

Fig. 5 is a transverse sectional view taken on line 5—5 of Fig. 1;

Fig. 6 is a transverse sectional view taken on line 6—6 of Fig. 1; and

Fig. 7 is a bottom plan view of the closure cap for one end of said pen.

Referring to the drawing more specifically by characters of reference, the numeral 10 designates a barrel, the hollow interior of which provides an ink reservoir 11. This reservoir is cylindrical in shape and is adapted for receiving and holding the supply of ink or other writing fluid and has disposed therein a piston, to be 25 presently more fully described, which piston is adapted for reciprocatory movement therein. The lower end of the barrel 10 is internally threaded, as shown at 12, within which is threaded a conventional form of nib end section 13, said 30 end section being provided with the customary nib 14. A suitable cap 15 is threaded to this end of the barrel 10 for enclosing the nib 14 when the latter is not in use.

35. Disposed within the barrel 10 is a helical or screw member 16 which is provided with a relatively steep pitch, said member being provided with a reduced portion 17, at one end thereof which reduced portion is adapted to be received in a central opening 18 provided in the nib end 40 section 13, said member 16 being swiveled within said opening 18, which opening forms a bearing therefor to permit rotary movement of said member 16. Said member 16 extends centrally 45 within said barrel 10 and is adapted for rotary movement therein as will be hereinafter more 50 fully explained.

The member 16 has mounted thereon a piston generally designated by the reference character 19, said piston consisting of a cylindrical mem- 55

ber 20, the interior of which is hollow and may be filled with a resilient material 21 which will snugly encase the member 16 to prevent the passage of ink past the piston 19. In the end 5 walls of the member 20 are provided suitable rectangular slots 22, as shown in Fig. 5, said slots being of a size and shape to permit the passage therethrough of the screw threads provided on the member 16.

10 The member 20 is provided with laterally extending annular flanges 23 and 24 between which is disposed the piston ring 25 formed from resilient material such as cork or the like. The laterally extending annular flanges 23 form opposed end abutments for the sleeve-like body or 15 piston ring 25 which resist the tendency of said member 25 to increase in length due to radial compression thereof when inserted in the cylinder or reservoir 11. By reason of this, and by 20 reason of the fact that the body 25 is made of resilient material, the piston will fit snugly within the cylinder and seal the same to prevent the passage of ink past the piston while permitting of the reciprocation of the piston within the pen 25 barrel. It may be noted at this time that instead of the resilient filling 21 provided within the member 20 to prevent the passage of ink past the piston, a plurality of suitable washers 30 of resilient material having rectangular openings similar to the openings 22 may be disposed within said member 20 for effectively preventing the passage of ink through the interior of the member 20.

The upper end of the barrel 10 is also internally threaded, as shown at 26, said threaded portion being adapted for receiving a threaded nut 27 and washer of suitable resilient material 28 and a second threaded nut 29. The washer 28 will securely fit around the body of the member 16 which is cylindrical in shape at that point and will form a further seal against the passage of ink should any ink escape past the piston 19.

The nut or washer 29 when in completely assembled position is disposed inwardly of the uppermost open end of the barrel 10 and the upper free end of the screw member 16 extends or projects beyond said member 29, as shown in Fig. 1. The upper end of the member 16 is bifurcated, as shown at 30, for a purpose 50 to be presently more fully described.

The uppermost edge of the barrel is of reduced diameter as shown at 31, thereby forming a shoulder 32. Adapted to be received over the reduced portion 31 is a cap member 33, said cap member being freely rotatable on the reduced portion 31 for actuating the screw member 16 in a manner to be now described.

Loosely mounted within the cap member 33 is an annular member 34 provided with a depending internally threaded portion 35 which is adapted to be threaded in the open threaded end of the barrel 10. The member 34 is provided with a central opening 36, said opening being of reduced diameter at its upper portion and is adapted to permit the passage therethrough of the member 37, which member has a threaded shank 38, the free end of which is rigidly and permanently secured to the cap 33, as shown in Fig. 1.

70 The member 37 is provided with a rectangular head 39, as shown in Fig. 3, which head is adapted to be received between the bifurcations in the end of the screw member 16. The head 39 is of such a size as to be received within the 75 enlarged portion of the opening 36 in the mem-

ber 34, but is larger than the diameter of the reduced portion of said opening, whereby said head 39 will complete the assembly of the member 34 within the cap 33. As already stated, the cap 33 is readily rotatable relative to the member 34 and by reason of the head 39 of the member 37 engaging between the bifurcations of the screw member 16, the rotation of said cap 33 will impart rotary movement to the screw member 16.

5 As already stated, the screw member 16 is swivelly mounted at its lower end in the nib end section 13, the reduced end 17 on said screw member providing an annular shoulder which takes the end thrust imparted to the end member 16 in one direction. The end thrust in the 15 other direction is taken by the threaded shank 38 of the member 37.

10 In assembling the pen, the nib end section is 20 screwed into one end of the barrel 10, the screw member 16 with its associated piston 19 being disposed within the barrel with the reduced portion 17 thereof received in the opening 18 provided in the nib end section 13. The members 27, 28 and 29 are then mounted in place, as 25 shown in Fig. 1. The members 27 and 29 are provided with diametrically disposed recesses 40 and 41, respectively, whereby the same may be readily assembled in operative position by 30 reason of a suitable tool having projections for disposition within said recesses. Similarly, the member 34 is provided with the recesses 42 which may be reached by a similar tool through the openings 43 provided in the cap portion 33 when it is desired to either assemble or disassemble the member 34 with the end of the barrel 10.

When the pen is completely assembled, as 35 shown in Fig. 1, it will be readily apparent that the rotation of the cap 33 will impart rotary 40 movement to the screw member 16, which member is held against longitudinal movement. The rotary movement of the member 16 will in turn 45 impart reciprocating movement to the piston 19 causing the same to move either up or down depending upon the direction of rotation. The nib end section 13 is provided with the openings 44 for permitting the passage of ink into and out of the reservoir 11.

When it is desired to fill the pen with ink or 50 other writing fluid, the nib end is inserted into an ink well with the piston in its lowermost position. Thereupon the piston is retracted to its uppermost position by rotation of the operating 55 screw member 16 by means of the cap 33. This will draw the ink into the pen barrel or reservoir 11 as will be obvious.

It will also be apparent that the rotation of the cap 33 in the opposite direction will cause the piston to descend to expel the ink from the 60 barrel should there be any in the barrel when that is found necessary or desirable.

As is customary, the body 10 of the pen will 65 be preferably constructed of an opaque material, so that the construction of the interior parts are obstructed or concealed from view. The screw member 16 as well as the other metal parts which go to make up the construction of my improved pen are preferably formed of a non-corrosive material, and, if desired, may be made of some light alloy, such as aluminum or the like, so as to be of a minimum weight.

The novel details of construction and the combination and arrangement of the parts of my improved pen result in an article having many 75

practical commercial advantages. It will be readily apparent that the structure may be quickly and economically manufactured, and by reason of the small number of parts may be 5 readily assembled in a minimum of time by practically unskilled labor. The construction of the several parts is such that the same will be durable and will not readily get out of operative order in use. Furthermore, the several parts 10 are so constructed and assembled within the barrel of the pen that the ink capacity of the same is materially increased over that of pens heretofore used, and particularly over that of pens of corresponding size employing the conventional compressible rubber sack.

It is believed that my invention, its mode of construction, assembly and operation, and many of its advantages should be readily understood from the foregoing without further description, 20 and should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A fountain pen comprising a barrel open at both ends, a plug removably fitted in the lower end of said barrel and having a fluid duct provided therein, removably fitted washers in the upper end of the barrel, said washers being disposed inwardly of the upper free end of the barrel, a spiral screw member journaled in said plug and said washers, the upper end of said screw member extending beyond the said washers, a piston in the barrel moved longitudinally by said screw member, a plug having a central opening removably fitted in the upper free end 40 of the barrel, and a rotatable cap mounted on the upper free end of the barrel having a member depending therefrom integrally connected therewith and extending through said last mentioned plug and having a driving connection 45 with said screw member.

2. A fountain pen comprising a barrel open at both ends, a plug removably fitted in the lower

end of said barrel and having a fluid duct provided therein, removable means for closing the other end of said barrel, a spiral screw member journaled in said plug and said last mentioned removable means, a piston in the barrel moved longitudinally by said screw member, said piston comprising a hollow cylinder closed at both ends and filled with resilient material, the opposed closed ends of said cylinder being provided with rectangular openings to permit the passage therethrough of said screw member, a piston ring of resilient material surrounding said piston and having a snug fit within the barrel, whereby the actuating of said screw member will impart longitudinal movement to said cylinder, and means including a rotatable cap mounted on the upper free end of the barrel and having a portion provided thereon for engaging said screw member for actuating the same.

3. A fountain pen comprising a barrel open at both ends, a plug removably fitted in the lower end of said barrel and having a fluid duct provided therein, removably fitted washers in the upper end of the barrel, said washers being disposed inwardly of the upper free end of the barrel, a spiral screw member journaled in said plug and said washers, the upper end of said screw member being bifurcated and extending beyond the said washers, a piston in the barrel moved longitudinally by said screw member, a resilient piston ring surrounding said piston and snugly fitted within said barrel, whereby the actuation of said screw member will impart only longitudinal movement to said piston, a removably fitted plug having a central opening extending therethrough for closing the upper open free end of the barrel, a member having a substantially rectangular head extending through said last mentioned plug with the head thereof received between the bifurcations of the screw member, and a rotatable cap mounted on the upper free end of the barrel and rigidly secured to said last mentioned member, whereby the rotation of said cap will impart rotation to said screw member.

PIETRO GULIZIA.
